(57) **CLAIM**

The ornamental design for a square funnel top container, as
shown and described.

DESCRIPTION

FIG. 1 is a top frontal perspective view of a square funnel
top container according to my new design;

FIG. 2 is a front view of the square funnel top container
shown in FIG. 1;

FIG. 3 is a back view of the square funnel top container
shown in FIG. 1;

FIG. 4 is a left side view of the square funnel top container
shown in FIG. 1;

FIG. 5 is a right side view of the square funnel top container
shown in FIG. 1;

FIG. 6 is a top view of the square funnel top container shown
in FIG. 1; and,

FIG. 7 is a bottom view of the square funnel top container
shown in FIG. 1.

The ornamental design which is claimed is shown in solid
lines in the drawings. The broken lines in the drawings are
for illustrative purposes only and form no part of the claimed
design.
